United States Patent Office

Des. 228,310
Patented Sept. 4, 1973

228,310

PAIR OF SPECTACLES

Robert L. Shaw, Wilbraham, Mass., assignor to American Optical Corporation, Southbridge, Mass.

Filed Mar. 22, 1972, Ser. No. 237,231

Term of patent 14 years

Int. Cl. D16—06
U.S. Cl. D57—1 F

FIG. 1

FIG. 2

FIG. 3

FIG. 1 is a front elevational view of a pair of spectacles embodying my new design;

FIG. 2 is a top plan view thereof, the temples being broken away for convenience of illustration;

FIG. 3 is an elevational view of one side of the pair of spectacles, the opposite side thereof being of substantially the same appearance.

I claim:

The ornamental design for a pair of spectacles, as shown and described.
